APPARATUS FOR REMOVABLY SUPPORTING
AND TENSIONING CLOTHESLINES

William L. Bodine, Elyria, Ohio

Application April 1, 1955, Serial No. 498,594

4 Claims. (Cl. 211—119.15)

This invention relates to a mechanism for supporting and tensioning a clothesline in which the supporting post or posts are demountably connected with sockets or similar receiving means buried in the ground, such means being located in the yard, or in any suitable place outside or inside the dwelling, the mechanism being supplied with tensioning means, to allow the clothesline to be made taut.

An object of the present invention is to provide a simple and efficient means for inserting and removing clothesline posts from a fixed socket located as desired, to form a firm temporary connection, as by providing the socket and post construction so as to prevent relative rotation of one with respect to the other. A further object of the present invention is to provide a simple and efficient mechanism for putting tension on the clothesline carried by said posts, this mechanism being adapted to securely lock said post in line tensioning position.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawings of a form of the invention, which may be preferred, in which:

Figure I is a perspective view of the clothesline supporting mechanism assembled in upright position.

Figure II is an elevation partly in section, showing the base of the post and the fixed socket.

Figure III is a section of the line III—III of Figure II.

Figure IV is an elevation of a part of the post and base member, with tensioning and locking mechanism.

Figure V is a perspective view of a portion of the locking mechanism.

Referring to the drawings and particularly to Figure I, it will be seen that I provide means for supporting a clothesline 10, said means including clothes posts 11 carrying cross arms 12 with hooks 13 for attachment to the clothesline 10.

The posts 11 are rectangular in cross section as shown and removably positioned in similarly shaped sockets 14, which sockets, as stated, are permanently set and anchored in the ground, or in the floor of a garage or basement.

In order to maintain the posts 11 in vertical position, when set in place in the sockets 14, I provide horizontal or ground supports 15 and upwardly extending diagonal brace members 16 and 17, these being pivotally connected near the top to the posts 11 as shown in Figure I.

The ground supports 15 have plates 18 at their outer ends for bearing against the ground or other supporting surface and are provided on their upper edges with a plurality of notches 19, for engagement with the lower ends 17' of the brace members 16 and 17 which are positioned in proper notches as required in positioning the clothesline.

Referring to Figures II and III of the drawings, it will

2

be seen that I provide means to temporarily lock the posts and sockets together, in each socket 14 a rigid cross pin 20 anchored securely to the socket by riveting or otherwise and I also provide the socket 14 with a short locking pin 21 secured to the socket wall, and the bottom of the post 11 is provided with semi-cylindrical openings 22 in the walls thereof, these openings adapted to seat on the cross pin 20 when the post is inserted in the socket 14. There is also provided in the post 11 a hole 23, so spaced from the openings 22 that the hole 23 is in line with the locking pin 21 when the post is seated on the cross pin 20. When the post 11 is inserted in the socket, as shown in the full line position (Fig. II), the posts are rotated about the cross pin 20 and the locking pin 21 will enter the hole 23 in the post, thus locking the post against withdrawal from the socket.

It will also be seen from inspection of Figure III, that by providing the post 11 substantially square in section and making the socket 14 also rectangular with the sides thereof closely fitting the post 11, relative rotation between the two in a horizontal plane is effectually prevented.

The diagonal braces 16 and 17 are adapted to be positioned in any one of the outer or inner notches 19 in the ground supports 15, this tending to place the posts 11 in upright position and hold them in place. Brace 17 also has additional tensioning and locking mechanisms, adapted to put great tension on the clotheslines and place them in taut condition.

This mechanism, indicated generally as 24 in Figures I, IV and V, is mounted on the upper section 25 of the brace 17, said section telescoping with lower section 26 and both sections being of substantially rectangular cross section. Referring to Figure IV the pivotal connection between the diagonal braces 16 and 17 and the upright posts 11 includes a pair of lugs 7 fixed to the posts 11. A transverse pivot pin 8 passes through suitable openings in said lugs as shown. This pivot pin 8 is located in position in the lugs 7 by cotter pins 9. Mounted on the upper section 25 is a bifurcated bracket arm 27 and pivoted thereto is a hand lever 28 and a locking dog member 29. The hand lever 28 carries a pawl member 30 pivotally connected thereto as at 31, said member 30 carrying an engaging projection or "pin" 32. The locking dog member 29 is also provided with an engaging boss 33, and the lower brace section 26 is provided with openings 34 on its upper surface and openings 35 on its lower surface, said openings being adapted for engagement by the projection 32 and the boss 33.

The hand lever 28 is as a whole pivoted as by pin 36 to the arm 27 while the same pin pivots the locking dog member 29 to the arm 27. As the center of gravity of the locking member 29 is to the right of the pivot 36, the same tends to swing and to bring the boss 33 against the surface of the brace member section 26, also this tendency acts to cause the boss 33 to enter any hole in the brace to which it is in register.

It will readily be seen therefore, that movement of lever 28 around pin 36 will first cause extension of the telescoped post, due to the engagement of the projection 32 with the hole 34, also that as the projection 33 on the dog member 29 moves along the lower surface of the member 26 it will be forced by gravity into one of the holes 35 therein.

Thus the two parts 25 and 26 will be held by the dog 29 while the lever 28 may be again raised till the projection 32 engages another hole 34 on the top surface of the member 26, when the action can be repeated till the extension of the brace member 17 is sufficient to put the clotheslines in extremely taut condition.

When it is desired to release the tension on the lines, this may be done by pressing upward on lever 37 integral

with dog member 29, whereby the boss 33 is withdrawn from engagement with one of the holes 35 in the lower section 26 of the brace member 17.

As soon as the tension is removed from the clothesline 10, the posts may readily be swung from vertical to inclined position, at which time the pin 21 will withdraw from the hole 23 in the post 11 and the same may readily be removed from the socket 14.

What I claim is:

1. In a removable clothes post assembly, a socket of predetermined cross sectional configuration adapted to removably support an upright post therein, said socket having a pivoting pin connecting opposite sides thereof; a locking pin fixed to said socket and located at right angles to said pivoting pin and extending partially into said socket from another portion of said socket; and a removable post having a lower end of predetermined cross sectional configuration smaller than said socket to fit therein to permit said lower end of said upright post to pass said pin, the cross sectional configuration of said socket and said post end constructed to prevent rotation therebetween, said end of said post having a pair of notches at the lower edge portions of said end to fit over said pivot pin in said socket and an opening in said lower end of said post to receive said locking pin on said socket, to retain said post in said socket when said post is swung to upright position with said notched end thereof pivoted on said pivot pin in said socket.

2. In a removable clothes post assembly, a socket of rectangular cross section adapted to removably support an upright post therein, said socket having a pivoting pin connecting opposite sides thereof; a locking pin extending partially into said socket from one of the other of said rectangular sides of said socket, said locking pin fixed to said socket and located at right angles to said pivoting pin; and a removable post having a lower end of rectangular cross section substantially smaller than said socket to fit therein to permit relative swinging movement between said post and said socket, said end of said post having a pair of notches at the lower edge of opposite sides of said end to fit over said pivot pin in said socket and an opening in one of the other sides of said rectangular lower end of said post to receive said locking pin on said socket, to retain said post in said socket when said post is swung to upright position with said notched end thereof pivoted on said pivot pin in said socket.

3. In a removable clothes post assembly, a pair of sockets of rectangular cross section adapted to removably support a pair of upright posts therein, said posts carrying cross bars to support clotheslines therebetween, each of said sockets having a pivoting pin connecting opposite sides thereof; a locking pin extending partially into said socket from one of the other sides of each socket, the pin in one socket facing the pin in the other socket, each of said locking pins being fixed to the socket and positioned at substantially right angles to the pivoting pin; and a pair of removable posts each having a lower end of rectangular cross section substantially smaller than a socket to fit therein to permit relative swinging move-

ment between said post and said socket, the end of one of said posts having a pair of notches at the lower edge of opposite sides of said end to fit over said pivot pin in the socket receiving said post; an opening the other side of the lower end of said post opposite the other post to receive said locking pin on said socket, to retain said post in said socket when said post is swung to upright position; the end of the other post having a pair of notches at its lower end to fit over the pivot pin in said socket into which said post extends and an opening in the side of said lower end of said post to receive said locking pin on its receiving socket, to retain said post in said socket, both said posts adapted to be swung away from each other to upright position with said notched ends pivoted on said pivot pin of said sockets.

4. In a removable clothes post assembly having a ground member, an upright clothes post and a two part diagonal member arranged to be positioned in extended and retracted positions, one part pivoted at the top to the upper part of said post, and the other part fitting at the bottom into a receiving notch in said ground member, manually operable self-locking extending and retracting means between said two parts of said diagonal member, comprising a pivot bracket secured to one of said members, a pair of series of holes in the other member; an operating lever pivoted to said bracket; a locking pivoted lever carried by said bracket, said lever having a boss for engaging one of said holes, in one of said series; means whereby said boss is released when said lever is operated; an operating pawl; said pawl pivoted at said operating lever and actuated by said lever, having a pin for normally engaging the other holes in said member; the construction arranged whereby said lever disengages said pin when said lever is operated to extend said two-piece extendable diagonal member; means whereby when said lever is moved in one direction, said pawl and pin forces said members apart, and said boss locks the same in extended position, and when said lever is moved in the opposite direction, said pin is released from said hole, whereby the two parts of said diagonal member return to retracted position.
